UNITED STATES PATENT OFFICE.

FRANK L. LLOYD, OF BALTIMORE, MARYLAND, ASSIGNOR TO THE CROWN CORK AND SEAL COMPANY OF BALTIMORE CITY, A CORPORATION OF MARYLAND.

PACKAGING-MACHINE.

1,372,030.

Specification of Letters Patent. Patented Mar. 22, 1921.

Application filed November 14, 1917. Serial No. 201,912.

To all whom it may concern:

Be it known that I, FRANK L. LLOYD, a citizen of the United States, residing at Baltimore, State of Maryland, have invented certain new and useful Improvements in Packaging-Machines, fully described and represented in the following specification and the accompanying drawings, forming a part of the same.

10 This invention relates to packaging machines. In certain types of packaging machines, for example, in certain bottle capping apparatus, the bottles to be capped are centered in capping position by the aid of a spider provided with bottle-receiving pockets, this spider being rotated with the bottle-supporting table to carry the bottles to and away from the position where the capping operation is performed. Such a spider is 15 usually designed for use with bottles of only one size and for rotation in only one direction.

20 It is one of the objects of the present invention to provide apparatus, including a bottle-centering spider, such that interchangeable spiders may be readily substituted to make the machine available for use with different sized bottles, and such that in case a spider of one rotational direction is used, it may readily be made available for use in the reverse direction.

25 It is a further object of the invention to provide apparatus including a bottle-centering spider, such that the spider may readily be adjusted on its drive shaft.

30 Still a further object of the invention is to provide apparatus of the type mentioned including a pocket-blocking plate for blocking off any given pocket to prevent the entrance of a bottle, such that the blocking plate may be securely but detachably held in place.

35 The following specification describes and the accompanying drawing illustrates apparatus constructed in accordance with the invention, it being understood that changes may be made in the form, construction and arrangement of the parts without departing from the invention, the form herein disclosed being a preferred embodiment thereof.

In the drawing—

Figure 1 is a transverse sectional view through a portion of a packaging machine

embodying the invention, showing the 55 bottle-centering spider from above;

Fig. 2 is a view of the same in vertical cross section, with parts in side elevation;

Fig. 3 is a detail view in vertical section of a portion of the apparatus shown in Fig. 60 2, and

Fig. 4 is a transverse section through Fig. 3.

The apparatus illustrated as an example, comprises a bottle-supporting table 10 rotated by a vertical shaft 11 to which it is connected by means of keys 12 fitting in keyways 13 formed in the shaft. This table is provided with a plurality of bottle pads 14 on which the bottles are seated during 65 the capping operation, three of these pads being shown in the present instance. At 15 is represented, more or less diagrammatically, a capping mechanism, which may be a single capping head or the capping position 70 of one of a plurality of heads having an orbital movement with respect to the table.

Above the table is a bottle-centering spider 16 comprising upper and lower plates 21, so that the bottles may be engaged at 80 two points as regards their height. These bottle-engaging plates, the form of which is clearly shown in Fig. 1, are provided with bottle-receiving pockets 17, those of the lower plate being in vertical alinement with 85 those of the upper plate. Three of these pockets are shown in the present instance. This spider is rotated as hereinafter described, and during the rotation of table and spider, bottles are fed in such manner that as 90 each pocket 17 reaches capping position, a bottle is centered in such pocket, so as to be properly placed for the capping operation.

Apparatus embodying the invention includes a spider comprising a bottle-engaging portion and a driven portion, the former being removably connected with the latter, and in the most advantageous embodiments the two elements are separate and have co-operating connecting portions, as, for example, portions mutually engaging with a slip fit. Although capable of various construction, in that illustrated the driven portion of the spider is in the nature of a hub 18 operably connected with the shaft 11 in 105 any suitable manner, as, for example, by the connection hereinafter described. The bottle-engaging portion comprises the two

plates 21 which are separate elements. In order that the bottle-engaging portion may be removably connected with the hub, or driven portion, the latter is provided with 5 upper and lower flanges 19 which carry pins 20, the upper pins extending upwardly and the lower ones downwardly, and the plates 21 are provided with openings having a slip fit over these pins. The spider plates of the 10 desired design are thus connected with the driven portion by slipping them onto the pins, the plates when in place bearing against the hub flanges 19, as appears in Fig. 2.

15 Means is provided for holding the connected parts together. Although capable of various constructions, in the present embodiment the ends of the hub 18 are threaded to receive upper and lower locking nuts 22 which are tightened against the spider plates 21 to clamp them against the hub flanges. A number of spider plates of different design to correspond with the different bottles to be capped, may be provided 20 and when it is desired to substitute different plates or to reverse the plates in use for rotation in the opposite direction, it is only necessary to loosen the nuts 22, slip the plates from the pins, slip on the substituted or reversed plates, and tighten the nuts 25 again.

30 Apparatus embodying the invention in its entirety includes, in connection with a drive shaft, a bottle-centering spider connected therewith in a manner to be adjusted thereon. This may be accomplished, for example, by a structure in which the spider is frictionally connected with the shaft. In the embodiment illustrated, the spider, as 35 already described, has a driven portion or hub 18. This hub is formed with a tapered bore, as shown in Fig. 2. Fitting in this bore, between the hub and the shaft, is a tapered or wedge-shaped split bushing 40 23. When this bushing is wedged into position, it acts to frictionally connect the hub of the spider with the shaft, so that the spider may be driven thereby, and at 45 the same time the connection is such that adjustment on the shaft may be readily made when desired.

50 Means is provided for forcing the bushing into position, for holding it in such position, and for readily withdrawing it therefrom. This may be accomplished, for example, by moving the bushing by means of a movable member having connection with the bushing. Although capable of various constructions, in the present embodiment, 55 threaded into the interior of the top nut 22 is a nut 24. This nut when in place engages the top of the bushing so that when the nut is screwed down it forces the bushing down into proper position to hold 60 the hub to the shaft. In order that oppo-

site movement of the nut may withdraw the bushing from such position, the top of the bushing is formed with a flange-like shoulder 123 which fits over an internal flange-like shoulder 124 on the nut 24, as appears 70 in Fig. 2. By screwing down the nut 24 the bushing is forced down into securing position and held there, and to re-seat, readjust or disassemble the parts, it is only necessary to move the nut in the opposite 75 direction, thus withdrawing the bushing and freeing the hub. In order to facilitate assembling, the nut 24 may be split.

80 The invention includes, in connection with the bottle spider, a blocking plate for preventing any one of the bottle-receiving pockets from receiving a bottle, one of these elements having a connecting member provided with a portion capacitated to make locking engagement with a portion of the 85 other element. As an example, the spider plate may have an opening for receiving a connecting member on the blocking plate, means being provided for locking the member in the opening. Although capable of 90 various constructions, in that shown a blocking plate 25 is provided of the form illustrated in Fig. 1, and such that when in place it blocks off one of the bottle-receiving pockets. Riveted in the blocking plate near its 95 ends, are flanged pins 26 carrying split spring washers 27 formed with a circumferential groove 28. Corresponding to these pins, openings 29 are formed in the spider plates and these openings are beveled to 100 form an interior flange 30, as more clearly appears in Fig. 3. When the blocking plate is in position, its inner edge bears against the flange 19 and it is secured to the spider by forcing the connecting pins into the 105 openings 29, the washer expanding to cause its groove to interlock with the flange 30. This securely locks the blocking plate to the spider, but removal is readily made by any suitable tool for disengaging the spring 110 washer from the flange 30. It will be seen from Fig. 1 that the openings 29 are spaced about the spider, so that the blocking plate may be inserted to block off any one of the several pockets. 115

120 Although the term "bottle" has been used throughout, it is to be understood that it is used in a broad sense, and as an example of any type of receptacle capable of use in the type of machine here involved. Furthermore, while the spider has been shown and described in connection with a bottle-capping mechanism, it is understood that the invention is not limited to such use.

125 What is claimed is:

1. In packaging machines, a bottle centering spider having a plurality of bottle engaging units, a blocking plate for rendering any one of said units inoperative, and a connecting member carried by one of said 130

elements, and having a portion capacitated to make locking engagement with a portion of the other of said elements.

2. In packaging machines, a bottle centering spider having a plurality of bottle engaging units, a blocking plate for rendering any one of said units inoperative, a connecting member on said plate, said spider having an opening for receiving said connecting member, and means for locking said member in said opening.

3. In a packaging apparatus, a driven hub, an interchangeable spider plate having a plurality of bottle receiving pockets formed therein, a flange on said hub on which said spider plate rests, and a dowel for locating the spider plate.

4. In a packaging apparatus, a driven hub, an interchangeable spider plate having a plurality of bottle receiving pockets formed therein, a flange on said hub on which the spider plate rests, a dowel for locating the spider plate, and means for detachably locking the spider plate in position.

5. In a packaging apparatus, a driven hub, an interchangeable spider plate having

a plurality of bottle receiving pockets formed therein, a flange on said hub on which the spider plate rests, a dowel for 30 locating the spider plate, and a lock nut in threaded engagement with said hub for detachably locking the spider plate in position.

6. In a packaging apparatus, a hub, 35 means operable from the end of the hub for locking the hub to a shaft, two reversible spider plates having a plurality of bottle receiving pockets formed therein, and means for detachably connecting said spider plates 40 to said hub at a distance from each other.

7. In packaging machines, a bottle centering spider having a plurality of bottle engaging units, a blocking plate for rendering any one of said units inoperative, a connecting member carried by one of said elements, the other element having an opening to receive the same, and a split spring washer on said connecting member for locking the blocking plate to the spider. 45 50

In testimony whereof I have hereunto set my hand.

FRANK L. LLOYD.
